UNITED STATES PATENT OFFICE.

DUNCAN MENZIES MCINTOCK, OF PAISLEY, SCOTLAND, ASSIGNOR TO CLARK AND COMPANY, LIMITED, OF PAISLEY, SCOTLAND.

MERCERIZING MACHINE.

Application filed March 11, 1924. Serial No. 698,523.

To all whom it may concern:

Be it known that I, DUNCAN MENZIES MCINTOCK, a subject of the King of Great Britain and Ireland, and residing at Anchor 5 Thread Mills, Paisley, Scotland, have invented certain new and useful Improvements in Mercerizing Machines, of which the following is a specification.

This invention relates to mercerizing machines and consists in an improvement in or modification of the invention protected by United States Application No. 595,843, dated the 20th day of October, 1922, having for its object to enable any desired portion 15 of the wash or liquid from the mercerizing tank to be diverted into a separate drain or otherwise treated to facilitate its recovery.

The invention also consists in an improvement in or modification of the apparatus 20 claimed in Specification No. 595,843 in which the outlet from the mercerizing tank is associated with a movable deflecting member, the position of which is determined by the position of the mercerizing tank.

25 The invention also consists in the provision of means whereby the deflecting member may be positioned independently of the mercerizing tank.

The invention still further consists in the 30 form of apparatus hereinafter described or indicated.

The accompanying drawings illustrate one form of apparatus in accordance with the invention:—

35 Figures 1 and 2 are front elevations showing a portion of a mercerizing machine in accordance with the invention with the parts in different positions;

40 Figure 3 is a side elevation partly in section.

In carrying my invention into effect, I construct my improved mercerizing machine in the manner described in the prior Specification No. 595,843. The outlet *a* from the 45 mercerizing tank *b* is associated with a deflecting member *c* suitably pivoted, as at *d*, so that in one position (shown in Figure 1) it will deflect the outflowing liquid to waste while in the other position (shown in Figure 2) it will convey the same to a separate drain *e* or other means by which the liquid 50 may be readily recovered.

The deflecting member *c* is adapted to be positioned by means of a suitable bar *f* 55 which is actuated by a catch *g* movable with

the mercerizing tank so that when the latter is in its lowermost position the deflecting member assumes one of its two positions while when the mercerizing tank is raised (as shown in Figure 2) the bar referred to 60 is also raised, thus moving the deflector into its second position. Such bar may, however, be released at any time during the operation of the machine by means of an adjustable cam tappet *h* adapted to co-operate with a 65 second tappet *i* (also adjustable) on a swinging or other bar *k* or other member adapted to be moved into contact with the deflector moving bar *f* or otherwise operating to release the said bar from its retaining catch, 70 thus re-positioning the movable deflector *c* there being, if necessary or desirable, a counterweight *l* on the lower end of the bar 75 *f* to facilitate the return of the parts when so released.

It will be understood that the invention is not to be limited to the particular details of construction which are hereinbefore given by way of example since it will be obvious that I may modify the form and arrangement of deflector, the number of positions which it may be made to assume and the particular means for controlling the movement of the deflector, depending upon any particular practical requirements that may 80 have to be fulfilled.

Having now described my invention what I claim as new and desire to secure by Letters Patent is:—

1. A mercerizing machine comprising in 90 combination a movable mercerizing tank having an outlet and a deflecting member associated with said outlet and movable with movement of said tank.

2. A mercerizing machine comprising in 95 combination a movable mercerizing tank having an outlet, a deflecting member associated with said outlet and movable with movement of said tank, and means for releasing said deflecting member from the 100 position to which it is moved by movement of the tank.

3. A mercerizing machine comprising in combination a movable mercerizing tank having an outlet, a deflecting member associated with said outlet and movable with movement of said tank, means for releasing said deflecting member after movement by 105 said tank and cam means controlling said releasing means.

4. A mercerizing machine comprising in combination a movable mercerizing tank having an outlet, a pivoted deflector associated with said outlet, a link secured to said deflector, and a projection on said tank which on movement of the tank engages said link to move said deflector.
5. A mercerizing machine comprising in combination a movable mercerizing tank having an outlet, a pivoted deflector associated with said outlet, a link secured to said deflector, a projection on said tank which on movement of the tank engages said link to move said deflector and means for causing a disengagement of said projec-

tion from said link independently of movement of the tank.

6. A mercerizing machine comprising in combination a movable mercerizing tank having an outlet, a pivoted deflector associated with said outlet, a link secured to said deflector, a projection on said tank which on movement of the tank engages said link to move said deflector and cam operated means for causing disengagement of said projection from said link independently of movement of the tank.

In testimony whereof I have signed my name to this specification.

DUNCAN MENZIES McLINTOCK.
